UNITED STATES PATENT OFFICE.

CHARLES HARTER, OF ST. LOUIS, MISSOURI, ASSIGNOR OF ONE-HALF TO JOHN E. O'BRIEN, OF ST. LOUIS, MISSOURI.

STEAM-BOILER.

1,249,079.

Specification of Letters Patent.

Patented Dec. 4, 1917.

Application filed June 8, 1917. Serial No. 173,524.

To all whom it may concern:

Be it known that I, CHARLES HARTER, a citizen of the United States of America, a resident of the city of St. Louis, State of Missouri, have invented certain new and useful Improvements in Steam-Boilers, of which the following is a full, clear, and exact description, reference being had to the accompanying drawings, forming a part of this specification.

My invention relates to a steam boiler of the fire tube type and it has for its object the provision of means in a boiler of this kind through the medium of which a continuous circulation of the water in the boiler is created, so that the water is constantly returned to the proximity of the fire chamber after it has circulated in a direction away from said chamber toward the opposite end of the boiler. The type of boiler to which my improvement is more particularly intended to be applied is that used in locomotives, and I will describe the invention as used in a locomotive boiler, with the understanding that in so doing I do not limit myself to the use of my improvement to boilers of this particular description.

The ordinary fire tube boiler used for locomotives comprises a shell including the boiler barrel, the fire box partially surrounded by the boiler barrel, the smoke box and tubes extending longitudinally of the barrel between the fire box and the smoke box, the said tubes serving to conduct smoke and hot gases from the fire box to the smoke box. While some heat is radiated from the tubes into the water around them, the greatest benefit of the heat produced in the fire box to produce steam is created immediately around the fire box, and as there is no means for creating a continuous circulation of water longitudinally of the boiler a very considerable quantity of the water is constantly subjected only to being heated by the tubes, and its temperature is not raised to the degree of the temperature of the water immediately adjacent to the fire box. Consequently, the production of steam in the boiler is not as rapid or as efficient as it would be if all of the water were subjected to the temperature adjacent to the fire box.

as the result of a constant circulation longitudinally of the boiler. It is the purpose of my invention to provide such circulation and thereby increase the efficiency of a fire tube boiler.

Figure I is a vertical longitudinal section of my steam boiler.

Fig. II is a horizontal section of the boiler barrel.

Fig. III is a vertical cross section on line III—III, Fig. I.

Fig. IV is an enlarged vertical cross section on line IV—IV, Fig. I.

Fig. V is an enlarged vertical section through one of the vertical steam pipes and a fragment of the dividing sheet extending longitudinally of the boiler barrel.

In the drawings A designates the barrel of a locomotive boiler having interiorly thereof at its rear end a fire box B, around which water in the boiler barrel is adapted to circulate. Between the tube sheet b at the end of the fire box and the tube sheet d at the opposite end of the boiler barrel are the fire tubes C through which smoke and hot gases are conducted to the smoke box D. These described elements being present in ordinary locomotive boilers, no invention is herein claimed for them.

To provide for circulation of water longitudinally of the boiler so that it will pass forwardly away from the fire box and then return to the fire box to be subjected to the higher temperature radiated therefrom, I arrange a dividing sheet 1 in the barrel A at a point above the bottom of the barrel, this dividing sheet extending from the fire box tube sheet b into proximity with the forward tube sheet d and extending transversely from side to side of the boiler barrel, as seen in Figs. II and III. Said dividing sheet serves to subdivide the boiler barrel into upper and lower channels, between which communication is preferably arranged for by providing one or more openings 2 in the division sheet at its end farthest removed from the fire box. While I prefer to furnish communication between the channels in the boiler barrel by providing an opening or openings as just mentioned, it is obvious that the same result would be

accomplished by making the division sheet of such length that it will terminate at a short distance from the forward tube sheet *d*.

In the use of my boiler the water at the 5 sides of and above the fire box *B* when heated rises and tends to move forwardly in the boiler barrel above the dividing sheet 1. In so doing it tends to force the water in front of it forwardly and to create a circulation 10 from the channel above the dividing sheet to the channel beneath the dividing sheet, so that the water in the lower channel will be forced toward the fire box and returned to circulate around said box, where it will be subjected to the higher 15 degree of heat radiated from said box. When the water in the boiler has been once heated, there is a constant circulation in the path just pointed out, and the efficiency 20 of the boiler is rendered much greater than the efficiency of an ordinary fire tube steam boiler lacking means for occasioning longitudinal circulation, as contemplated by my invention.

To avoid the occurrence of a steam pocket 25 beneath the dividing sheet 1, I provide means whereby any steam created in the channel beneath the dividing sheet may be vented therefrom to the steam space at the 30 top of the boiler barrel. The means utilized for this purpose preferably comprises a series of vertical steam vent pipes 3 extending through the dividing sheet 1 and secured thereto by nuts 4 and 5 located above and 35 below the dividing sheet. The upper ends of these steam pipes are secured in any suitable manner to stay bars 6 attached to the boiler barrel. The dividing sheet 1 is arched transversely, as shown in Fig. III, 40 to cause the steam in the lower channel to flow toward the steam pipes 3, which extend upwardly from the highest portion of the arch.

If the dividing sheet 1 is riveted to the 45 tube sheet *b*, the heat generated in the fire box will be transmitted through two thicknesses of metal at the junction of these parts, and the joint will be subjected to a much higher degree of heat than adjacent portions 50 of the fire box. The tube sheet *b* is therefore preferably separated a slight distance from the adjacent end of the dividing sheet (Fig. I) to provide a restricted passageway wherein some of the hot water rises to avoid 55 the danger of overheating the end of the dividing sheet.

Fig. III shows that the dividing sheet is arranged above one group of the tubes 2 and below another group of the tubes. This is a 60 very important feature of the invention, and several advantages are obtained by arranging the dividing sheet between the groups of tubes. If the dividing sheet was located entirely below all of the tubes in an ordinary 65 locomotive boiler, the results I obtain would

not be accomplished. The lower channel formed below the dividing sheet would be so small that no appreciable circulation would be obtained by the use of the dividing sheet.

By arranging the dividing sheet 1 between the upper and lower groups of tubes, as herein shown, I form two large, unobstructed channels wherein the water circulates freely and very rapidly. The hottest 70 water circulates freely and quickly in the large upper passageway above the dividing sheet, the temperature of the water being gradually reduced as it flows away from the fire box to the passageway 2 in the dividing sheet 1. The relatively cool water flows 75 downwardly through the passageway 2 and into the large, unobstructed lower channel leading to the lower portion of the fire box. Owing to the peculiar manner in 80 which the dividing sheet is combined with the upper and lower groups of tubes, a rapid circulation is obtained and the efficiency of the boiler is greatly increased. Furthermore, both groups of tubes are constantly 85 subjected to the cleansing action of a large body of water, moving at a high velocity toward and away from the water leg around the fire box. As a consequence, the formation of scale on the tubes is prevented and 90 the sediment is forcibly carried to the water leg, where it drops by gravity to the bottom of said leg. The water passing from the lower channel (Fig. I) flows over the shallow water leg at the front of the fire box and 95 rises at the sides of the fire box.

I claim:

1. The combination, in a boiler of the character described, of a boiler barrel, a fire box at one end of said boiler barrel partially surrounded by said barrel, groups of fire tubes in said barrel leading from said fire box, and a dividing sheet arranged between the groups of tubes and subdividing the portion of said boiler barrel through 105 which said tubes extend into a plurality of channels permitting circulation of water longitudinally of the boiler barrel to and from said fire box, said dividing sheet being thus combined with the boiler barrel and 110 fire box to provide a continuous endless passageway through which the water, rising at the fire box, is forcibly circulated toward the opposite end of the boiler and then 115 back to the fire box.

2. The combination, in a boiler of the character described, of a boiler barrel, a fire box at one end of said boiler barrel partially surrounded by said barrel, groups of fire tubes in said barrel leading from said 125 fire box, and a horizontal dividing sheet arranged in said barrel between said groups of tubes and dividing the barrel into upper and lower channels through which water may 130 circulate longitudinally of the boiler barrel

to and from said fire box, said dividing sheet being thus combined with the boiler barrel and fire box to provide a continuous endless water passageway through which the water, 5 rising at the fire box, is forcibly circulated along the groups of tubes and back to the fire box.

3. The combination, in a boiler of the character described, of a boiler barrel, a fire box at one end of said boiler barrel partially surrounded by said barrel, upper and lower groups of fire tubes in said barrel leading from said fire box and a longitudinal dividing sheet secured in the barrel between the 10 upper and lower groups of tubes and dividing the barrel into large upper and lower channels through which the water can circulate freely, longitudinally of the barrel, to and from the fire box, a transverse passageway being formed near the end of the dividing sheet farthest from the fire box to allow the water to circulate downwardly from the upper channel above the dividing sheet to the lower channel below said dividing sheet, said dividing sheet being thus combined with the boiler barrel and fire box to provide a continuous endless water passageway 15 through which the water, rising at the fire box, is forcibly circulated along the upper group of tubes to a point remote from the fire box and then back along the lower group of tubes to the fire box.

4. The combination, in a boiler of the character described, of a boiler barrel, a fire box at one end of said boiler barrel partially surrounded by said barrel, upper and lower groups of fire tubes in said barrel leading from said fire box, and a longitudinal dividing sheet extending across the barrel between the upper and lower groups of tubes to provide a large, unobstructed upper channel for the circulation of water from the upper portion of the fire box and a large, unobstructed lower channel for the return 20 of the water to the lower portion of the fire box, a transverse passageway being formed near the end of the dividing sheet farthest from the fire box to allow the water to circulate downwardly from the group 25 of tubes in the upper channel above the dividing sheet to the group of tubes in the lower channel below said dividing sheet, said dividing sheet being thus combined with the boiler barrel and fire box to provide a continuous endless water passageway 30 through which the water, rising at the fire box, is forcibly circulated along the upper group of tubes to a point remote from the fire box and then back along the lower group of tubes to the fire box.

5. The combination, in a boiler of the character described, of a boiler barrel, a fire box at one end of said boiler barrel partially surrounded by said barrel, a water 35 leg being formed around the fire box and

said water leg being relatively shallow at the front of the fire box, upper and lower groups of fire tubes in said barrel leading from said fire box, and a longitudinal dividing sheet extending across the barrel 40 between the upper and lower groups of tubes to provide a large unobstructed channel for the circulation of water from the upper portion of the water leg and a large unobstructed lower channel for the return 45 of the water to the lower portion of said water leg, said lower channel being in free communication with the relatively shallow portion of the water leg at the front of the fire box, a transverse passageway being 50 formed near the end of the dividing sheet farthest from the fire box to allow the water to circulate downwardly from the group of tubes in the upper channel, above the dividing sheet, to the group of tubes in 55 the lower channel below said dividing sheet, said dividing sheet being thus combined with the boiler barrel and fire box to provide a continuous endless water passageway 60 through which the water, rising at the fire box, is forcibly circulated along the upper group of tubes to a point remote from the fire box and then back along the lower group of tubes to the fire box, and a restricted water passageway being formed 65 between the fire box and the adjacent end of the dividing sheet.

6. The combination, in a boiler of the character described, of a boiler barrel, a fire box at one end of said boiler barrel partially surrounded by said barrel, upper and lower groups of fire tubes in said barrel leading from said fire box, a longitudinal dividing sheet secured in the barrel between the upper and lower groups of tubes and 70 dividing the barrel into large upper and lower channels through which the water can circulate freely, longitudinally of the barrel, to and from the fire box, a transverse passageway being formed near the end of the dividing sheet farthest from the fire box to allow the water to circulate downwardly from the upper channel above the dividing sheet to the lower channel below 75 said dividing sheet, said dividing sheet being thus combined with the boiler barrel and fire box to provide a continuous endless water passageway 80 through which the water, rising at the fire box, is forcibly circulated along the upper group of tubes to a point remote from the fire box and then back along the lower group of tubes to the fire box, and a restricted water passageway being formed 85 between the fire box and the adjacent end of the dividing sheet.

7. The combination, in a boiler of the character described, of a boiler barrel, a fire box at one end of said boiler barrel partially surrounded by said barrel, fire tubes in said barrel leading from said fire box, a horizontal dividing sheet in the portion of 90

- 4
- said barrel through which said tubes extend by which said portion of the barrel is subdivided into upper and lower channels through which water may circulate longitudinally of the boiler barrel to and from said fire box, said dividing sheet being thus combined with the boiler barrel and fire box to provide a continuous endless passageway through which the water, rising at the fire box, is forcibly circulated toward the opposite end of the boiler and then back to the fire box, and steam conducting pipes leading upwardly from said dividing sheet whereby steam may be conducted from the channel beneath said dividing sheet to the steam space at the top of the boiler barrel.
8. The combination, in a boiler of the character described, of a boiler barrel, a fire box at one end of said boiler barrel partially surrounded by said barrel, groups of fire tubes in said barrel leading from said
- 5 10 15 20
- fire box, a horizontal dividing sheet in the portion of said barrel through which said tubes extend by which said portion of the barrel is subdivided into upper and lower channels through which water may circulate longitudinally of the boiler barrel to and from said fire box, said dividing sheet being thus combined with the boiler barrel and fire box to provide a continuous endless passageway through which the water, rising at the fire box, is forcibly circulated along the groups of tubes and back to the fire box, said dividing sheet being arched transversely, and a steam conductor leading upwardly from the relatively high portion of the arch to conduct steam from the lower channel to the steam space at the top of the boiler barrel.
- 25 30 35
- In testimony that I claim the foregoing I hereunto affix my signature.
- CHARLES HARTER.
